UNITED STATES PATENT OFFICE.

CORNELIUS C. DIBBLE, OF STARRUCCA, PENNSYLVANIA.

CHAIN FASTENER.

Application filed May 6, 1927. Serial No. 189,268.

The present invention relates to improvements in fastening devices and has reference more particularly to a simple and efficient means for securing the free ends of a chain together.

One of the important objects of the present invention is to provide a chain fastener which is particularly adapted for use in connecting the end links of the side chains of an automobile skid chain so that the skid chain will be properly secured on the vehicle wheel, the fastening means being of such construction as to prevent the same becoming accidentally opened, yet permitting the fastener to be readily and easily actuated without the loss of any considerable length of time or labor.

A still further object is to provide a chain fastener of the above mentioned character which is simple in construction, inexpensive, strong and durable and further well adapted to the purpose for which it is designed.

Other objects and advantages of the invention will become apparent from the following description taken in connection with the accompanying drawing.

In the accompanying drawing forming part of this application:

Figure 1 is a side elevation of the chain fastener embodying my invention showing the manner in which the free end link of a chain is locked in the body portion of the fastener.

Figure 2 is a top plan view of the fastener per se.

Figure 3 is an end elevation, and

Figure 4 is a fragmentary detail perspective view of the rear portion of the body.

In the drawing wherein for the purpose of illustration is shown the preferred embodiment of my invention, the numeral 1 designates generally my improved chain fastener, the same comprising a channel shaped body of a suitable length, the bottom of the body being designated by the numeral 2, while the upstanding sides are indicated by the reference characters 3 and 4, respectively. A pair of registering openings 5 and 6 are formed in the rear ends of the sides 3 and 4 of the channel shaped body whereby one end link A of a chain may be permanently secured to the body at the rear end thereof in the manner clearly shown in Figure 1.

The upper edges of the sides 3 and 4 of the channel shaped body at the forward end

thereof are cut away to provide a bill or hook 7 for engagement with the other end link B of the chain and a seat 8 is provided for this end link B at the bottom of the hook or bill 7 in the manner clearly shown in Figure 1 of the drawing.

The upper edges of the sides are further cut away as at 9 to provide a means for facilitating the ready and easy gripping of the locking bail, the construction of which will be presently described.

The sides are further formed with elongated longitudinally extending slots 10 and 11, respectively with which communicate the vertically disposed notches 12 and 13, respectively, in the manner more clearly disclosed in Figure 4.

Also forming an important part of the present invention is the locking bail designated generally by the numeral 14 and the same is formed of a single elongated strand of spring wire bent into substantially U-shaped formation in top plan as more clearly disclosed in Figure 2. The locking bail is of a width less than the inner width of the body and the sides 15 and 16 as well as the crown or face portion 17 of this U-shaped locking bail are disposed within the body.

A loop 18 is formed at the forward end of the base or bottom portion 2 of the body for engagement over the base or crown portion 17 of the U-shaped locking bail 14 and this provides a pivotal connection between the forward end of the body and the adjacent end of the locking bail whereby said locking bail may be adapted to swing upwardly between the sides 3 and 4 of the channeled body.

The outer free ends of the arms 15 and 16 of the U-shaped locking bail are disposed outwardly as illustrated at 19 and 20 respectively, and formed on the outer end of the laterally disposed portions are the ears 21 and 22 respectively, the same being disposed at right angles with respect to the lateral portions 19 and 20 as is more clearly disclosed in Figure 2. These ears 21 and 22 are of such shape and size as to be permitted to pass freely through the longitudinally extending slots 10 and 11 formed in the sides 3 and 4 respectively.

The arms of the U-shaped locking bail adjacent the base portion 17 thereof are bent to form the nose portions 23 which close the seat 8 for locking the end link B against

disengagement from the hook or bill 7. The intermediate portions of the arms are furthermore curved upwardly as indicated at 24 and the curved portions are disposed slightly above the lower edges of the cut out portions 9 formed in the upper edges of the intermediate portions of the sides 3 and 4 of the body in the manner clearly disclosed in Figure 1.

The curved portion 24 provide handles for actuating the spring U-shaped bail 14 and when the parts are arranged in Figure 1 of the drawing, the lateral projections 19 and 20 formed on the free ends of the arms 15 and 16 of the U-shaped locking bail 14 will be disposed within the vertically arranged notches 12 and 13, and due to the resiliency of the locking bail, the same will be held in its locking positions, so that the end link B cannot be possibly disengaged from the hook or bill 7 formed at the forward end of the body.

Whenever it becomes necessary to disengage the end link B from the fastener, the curved or handle forming portions 24 of the arms are grasped and pressed inwardly and in the mean time, a downward pressure is exerted on the bail to move the lateral projecting portions 19 and 20 out of engagement with the notches 12 and 13 and when the ears 21 and 22 are in registry with the slots 10 and 11, and a further inward pressure on the arms of the U-shaped locking bail is exerted, the ears may then be moved inwardly out of the slots and the free end of the locking bail will then be permitted to be swung upwardly, thus removing the nose portion 23 out of the body whereby said link B may then be free to be removed from the fastener in an obvious manner.

It will thus be seen from the foregoing description that I have provided a chain fastener which may be readily and easily actuated for opening or closing the same and will at all times be positive and efficient in securing the end links of the chain together. Furthermore, the simplicity of my device enables the same to be constructed at a very low cost and will at all times be strong and durable.

While I have shown the preferred embodiment of my invention, it is to be understood that minor changes may be made in the size, shape and arrangement of parts without departing from the spirit of the invention and the scope of the appended claims.

Having thus described the invention, what I claim is:

1. A chain fastener comprising a body, one end link of a chain being permanently attached to one end of the body, the other end of the body being formed with a hook for engagement with the other end link of

the chain, and means for securing the link against disengagement from said hook, said means comprising a substantially U-shaped locking bail, the base portion thereof being operatively connected to the hooked end of the body, said bail extending across the open side of the hook, and cooperating means between the free ends of the arms of the U-shaped bail, and said body for securing the bail in a locked position in the body, said last mentioned means comprising lateral projections formed on the free ends of the arms of the U-shaped bail, said body being formed with openings in the sides thereof in which said lateral projections are detachably disposed.

2. A chain fastener comprising a channeled body, one end of a chain being permanently attached to one end of the body, the other end of the body being formed with a hook for engagement with the other end link of the chain, the sides of the body being formed with a seat adjacent the hook for said last mentioned end link, a substantially U-shaped locking bail secured at the crown portion thereof to the hooked end of the body, the arms of the U-shaped bail being bent to provide a nose for closing the entrance to said hook to retain the link in the seat provided therefor, and cooperating means between the free ends of the arms of the locking bail and the sides of the body for securing the bail in its locking position.

3. A chain fastener comprising a channeled body, one end of a chain being permanently attached to one end of the body, the other end of the body being formed with a hook for engagement with the other end link of the chain, the sides of the body being formed with a seat adjacent the hook for said last mentioned end link, a substantially U-shaped locking bail secured at the crown portion thereof to the hooked end of the body, the arms of the U-shaped bail being bent to provide a nose for closing the entrance to said hook to retain the link in the seat provided therefor, and cooperating means between the free ends of the arms of the locking bail and the sides of the body for securing the bail in its locking position, said last mentioned means comprising lateral projections formed on the free ends of the arms, laterally extending ears on the outer ends of the lateral projections, the sides of the channel body being formed with registering longitudinally extending slots through which the ears are freely slidable, said sides being formed with vertical notches which register with the respective slots, and in which the lateral projections on the free ends of the arms are disposed.

In testimony whereof I affix my signature.
CORNELIUS C. DIBBLE.
